Claims priority, application Germany December 10, 1952

6 Claims. (Cl. 260—270)

Our present invention relates to heterocyclic carboxylic acid hydrazide metal complexes produced by the interaction of compounds, particularly salts, of metals of the second to eighth groups of the periodic system with heterocyclic carboxylic acid hydrazides such as isonicotinic acid hydrazide and pyromucic acid hydrazide and to procedure for preparing such metal complexes.

It is known that isonicotinic acid hydrazide is capable of forming complex compounds with bivalent copper ions, which complex compounds have been alleged to show tuberculostatic activity. It has been found, however, that the alleged tuberculostatic activity is very slight and that the compatibility of such complex compounds is greatly restricted because of the relatively high toxicity of copper. While it has been previously known that copper has the capacity of forming complex compounds when employed in a form making copper ions available, the previous work has been shown to be specific for copper only.

It was, therefore, surprising and unpredictable that isonicotinic acid hydrazide and hydrazides of other heterocyclic carboxylic acids having tuberculostatic activity possess a marked capacity for forming metal complexes with organic and inorganic metal compounds to permit the production of metal complexes with various metals of groups 2-8 of the periodic system. We have found that among these metal complexes there are a number of new heterocyclic carboxylic acid hydrazide derivatives which are distinguished by excellent chemotherapeutic activity together with good compatibility. In this respect we have found that many of the metal complexes to be hereinafter described are markedly superior to isonicotinic acid hydrazide, as such, and to its copper complex compound. As will be hereinafter also set forth, certain of our new derivatives are of value in animal therapy.

According to our invention, heterocyclic carboxylic acids are employed as the starting material. Examples of heterocyclic carboxylic acids which are useful in our invention are isonicotinic acid, nicotinic acid, pyromucic acid, γ -pyridine carboxylic acids, derivatives of γ -pyridine carboxylic acids substituted in the nucleus by alkyl radicals, pyridyl acetic acids, pyridyl acrylic acids, pyridyl crotonic acids and other pyridyl alcanoic acids, quinoline carboxylic acids and pyrimidine carboxylic acids. These acids are converted into their hydrazides in known manner by reacting their esters, chlorides or anhydrides with hydrazine or with compounds yielding hydrazine.

We have found that various organic and inorganic metal compounds of complex-forming metals of groups 2-8 of the periodic system can be successfully utilized but we preferably employ inorganic metal salts as these are particularly effective. In using metals having more than one valence, those salts are preferred in which the metals have their lower valency to avoid or minimize oxidation of the heterocyclic carboxylic acid hydrazide. Thus, for instance, ferrous sulfate is very useful in the formation of our new metal complexes and is preferable

2

to the use of ferric chloride, which may give rise to some difficulties when used under conditions similar to those of ferrous sulfate, but it is to be understood, nevertheless, that our invention is not restricted to the use of metal salts in which the metal is in its lower valency form. Metal sulfates have been found to be particularly advantageous since they frequently yield only slightly soluble complexes with the heterocyclic carboxylic acid hydrazides. We may also employ metal salts of hydrohalic acids, nitric acid, acetic acid and other inorganic and organic acids. In addition, complex compounds which add further ligands or exchange ligands may be employed under appropriate conditions. Metal compounds may, furthermore, be employed which do not have a salt-like character, such as the metal alcoholates and the reaction products of metals with acetyl acetone, and such have been found to be useful in and applicable to our invention.

The selected components are reacted in an aqueous medium or in organic solvents. Methyl alcohol has been found to be particularly useful and desirable as an organic solvent but other organic solvents may also be successfully employed, such as ethyl alcohol, acetone, tetrahydrofuran, formamide, dimethylformamide and pyridine. When the reaction is carried out in the presence of ligands capable of forming complexes, such as ammonia, amines and cyanogen ions, these become incorporated into the new metal complexes.

Our new metal complexes are generally characterized by being well crystallized compounds showing valuable therapeutic properties and in the therapeutic application of our new preparations only part of the hydrazide of the heterocyclic carboxylic acid may be converted into the metal complex or the metal complexes may be used in admixture with one another or admixed with the heterocyclic carboxylic acid hydrazide and these mixtures employed therapeutically.

The invention is illustrated by the following examples without limiting it thereto:

Example 1

An aqueous solution of 56.2 grams of crystallized ferrous sulfate of the formula $\text{FeSO}_4 \cdot 7\text{H}_2\text{O}$ in 100 cc. of water is added to a solution of 13.7 grams of isonicotinic acid hydrazide in 100 cc. of water at 45° C. A light brown solution is formed from which light brown crystals separate after a short time. The crystals are suction filtered after two hours and washed with water. 32 grams of the brown iron complex are obtained, which slowly become dark brown upon heating to above 200° C. The filtrate of the reaction mixture still contains abundant quantities of ferrous ions. It is, therefore, possible to use only half the quantity of iron sulfate; by doing so, however, a somewhat lesser yield (30 grams) is obtained. An excess of ferrous sulfate is thus preferred. The product may be represented by the formula:

Example 2

27.4 grams of isonicotinic acid hydrazide are dissolved in 250 cc. of boiling methanol. A solution of 30 grams of ferrous sulfate ($\text{FeSO}_4 \cdot 7\text{H}_2\text{O}$), which has been prepared at low temperature, is added to the hydrazide solution. It is to be noted that the ferrous sulfate solution must be prepared carefully and rapidly since, otherwise, precipitation occurs very soon. Upon combining the solutions a voluminous brownish-yellow precipitate forms instantly. The combined solutions are boiled on the water-bath for 10 minutes and the reaction product is suction filtered while hot and washed with a hot methanol solution. After drying at room temperature 34 grams

acid, Me is the metal, X is the anion or anionic portion of the metal compound employed and solvent is water or alcohol of crystallization. For example, when isonicotinic acid hydrazide and cobalt sulfate ($\text{CoSO}_4 \cdot 7\text{H}_2\text{O}$) are employed, R is $\text{C}_5\text{H}_4\text{N}$, Me is Co, X is SO_4 and solvent is $3\text{H}_2\text{O}$. In such case, therefore, as set forth in Example 6, the new metal complex responds to the formula—

Depending upon the particular metal, the particular inorganic or organic compound thereof and the solvent employed, the general formula varies as to the proportions of Me and X in the MeX component with each other and with relation to the heterocyclic carboxylic acid hydrazide and also varies as to the presence of water or alcohol of crystallization. In general, it is preferred to utilize metal compounds in which the metal is in a lower stage of oxidation since this avoids destruction of free heterocyclic carboxylic acid hydrazide and simplifies the preparation of the new metal complexes.

Thus, the new metal complexes, as exemplified by isonicotinic acid hydrazide metal complexes, may be summarized as follows:

1. $\text{C}_5\text{H}_4\text{N}-\text{CO}-\text{NH}-\text{NH}_2 \cdot 1\text{MeX}_2$; e. g.,
 $\text{C}_5\text{H}_4\text{N}-\text{CO}-\text{NH}-\text{NH}_2 \cdot \text{CoSO}_4 \cdot 3\text{H}_2\text{O}$
 $\text{C}_5\text{H}_4\text{N}-\text{CO}-\text{NH}-\text{NH}_2 \cdot \text{FeSO}_4 \cdot 3\text{H}_2\text{O}$
2. $\text{C}_5\text{H}_4\text{N}-\text{CO}-\text{NH}-\text{NH}_2 \cdot 1\text{MeX}_2$; e. g.,
 $2\text{C}_5\text{H}_4\text{N}-\text{CO}-\text{NH}-\text{NH}_2 \cdot \text{FeSO}_4 \cdot \text{solvent}$
 $2\text{C}_5\text{H}_4\text{N}-\text{CO}-\text{NH}-\text{NH}_2 \cdot \text{MgSO}_4 \cdot \text{H}_2\text{O}$
3. $\text{C}_5\text{H}_4\text{N}-\text{CO}-\text{NH}-\text{NH}_2 \cdot 2\text{MeX}_2$; e. g.,
 $3\text{C}_5\text{H}_4\text{N}-\text{CO}-\text{NH}-\text{NH}_2 \cdot 2\text{CoCl}_2 \cdot 6\text{H}_2\text{O}$
4. $\text{C}_5\text{H}_4\text{N}-\text{CO}-\text{NH}-\text{NH}_2 \cdot 3\text{MeX}_2$; e. g.,
 $4\text{C}_5\text{H}_4\text{N}-\text{CO}-\text{NH}-\text{NH}_2 \cdot 3\text{ZnCl}_2 \cdot \text{C}_2\text{H}_5\text{OH}$
 $4\text{C}_5\text{H}_4\text{N}-\text{CO}-\text{NH}-\text{NH}_2 \cdot 3\text{MnCl}_2 \cdot \text{solvent}$

The molecular ratio of hydrazide to metal atom varies from approximately 1:0.25 in the case of magnesium (Example 4) or nickel (Example 5) to 1:2.0 in the case of iron (Example 1).

Our invention, therefore, covers not only new metal complexes of heterocyclic carboxylic acid hydrazides but also the process of preparing the same. The new metal complexes are generally characterized by excellent

tuberculostatic activity coupled with good compatibility and non-toxicity and are suitable for employment in both human and animal therapy.

The scope of the invention is defined by the appended claims

We claim:

1. A metal complex of isonicotinic acid hydrazide having the formula:

in which MeX is a metal compound wherein Me is a metal selected from the group consisting of iron, cobalt, manganese, magnesium, antimony, nickel and zinc, X is the anion of the metal compound MeX and solvent represents at least 1 mol of solvent of crystallization selected from the group consisting of water, methanol and ethanol.

2. The complex having the formula

3. The complex having the formula

4. The complex having the formula

5. The complex having the formula

6. The complex having the formula
